ENGINE

Edward T. Vincent, Detroit, Mich., assignor to
 Continental Motors Corporation, Detroit, Mich.,
 a corporation of Virginia

Application April 12, 1935, Serial No. 15,978

1 Claim. (Cl. 74—580)

My invention relates to engines and more particularly to internal combustion engines of the radial cylinder type operated on the two stroke cycle. More particularly, my present invention is related to the improvement in many structural details of an engine of the character described whereby to facilitate and improve the engine performance and to further provide a construction which may be readily and economically assembled and serviced.

An object of my present invention is to provide an improved engine assembly embodying a plurality of radially extending cylinders and an associated connecting rod assembly, so constructed and arranged as to maintain friction and power losses at a minimum, whereby to generally improve engine operating conditions. Although the construction, as hereinafter described, is more particularly adapted for an engine of the two stroke cycle type, it will be apparent to those skilled in the art, that the principles of my invention may be incorporated in engines other than those of the type herein particularly illustrated.

A further object of my present invention is to provide for a simple and improved manifold construction for a radial engine employing a plurality of banks of radially extending cylinders, the present construction being constructed and arranged to facilitate assembly and to provide an engine of minimum weight and economical in construction.

For a more detailed understanding of my invention, reference may be had to the accompanying drawings which illustrate one form which my invention may assume, and in which:

Fig. 1 is an end elevational view of my improved radial engine showing a portion of the same broken away to illustrate one of the engine cylinders in vertical cross-section, and

Fig. 2 is a longitudinal fragmentary sectional view through the engine illustrated in Fig. 1, and illustrating in more detail my improved connecting rod assembly and crankcase structure which is especially adapted for a multi-bank radial engine of this type.

I have chosen for purposes of illustration to show my invention as embodied in a multi-bank, multi-cylinder radial two stroke cycle engine, though it will be obvious that the invention as broadly claimed herein is adaptable to other types of engines as well. The present engine in general is provided with a crankcase structure 10, which is so arranged as to support a plurality of cylinder structures 11 radially about the engine crankshaft 12. The particular engine herein illustrated

is a sleeve valve engine and is arranged with suitable intake and exhaust ports 13 and 14 respectively in the cylinder walls, said ports being controlled by the sleeve valve means for controlling the engine cyclical events. More particularly, my invention is incorporated with a sleeve valve engine of the type employing a single sleeve of the combined movement type.

The crankcase structure 10 is composed of crankcase sections assembled end to end as clearly illustrated in Fig. 2, said sections being preferably secured together by means of bolts or other fastening devices 15. The crankcase sections are each provided with webs or other crankcase portions 16 each adapted for carrying a bearing 17 15 for supporting the crankshaft bearing portions 18, substantially intermediate each of said banks of cylinders, and preferably each crankcase section is arranged to support a pair of radial cylinder banks, one of the webs 16 being preferably arranged between these parallel banks of engine cylinders while the other is arranged to lie intermediate a bank of cylinders of one crankcase section and an adjacent bank of cylinders carried by the adjacent crankcase section.

The crankcase structure as herein illustrated is preferably constructed to provide inner and outer crankcase wall portions 19 and 20 respectively, these crankcase wall portions being spaced to provide an annular chamber 21 extending circumferentially around the crankcase and communicating with the intake ports 13 of the engine cylinders. Preferably the chambers 21 encircle the cylinders and it will be noted that the chambers 21 of each crankcase section are in open communication, and thus the intake manifold portion, extending circumferentially around said crankcase, provides an intake manifold which is common to all of the radially extending cylinders of all the banks.

It will be noted that the engine cylinders herein illustrated are each provided with a single sleeve valve means 22, and in the type of sleeve valve engine herein illustrated, it will be noted that the sleeve valve means is moved with a combined 45 oscillating and reciprocating motion by means of sleeve driving or actuating cranks 23. The sleeve actuating cranks 23 are supported in bearings 24 carried by the crankcase and actuated by means of a sleeve driving eccentric 25, this eccentric 50 driving the eccentric crank 26 of the sleeve actuating means in any well known and suitable manner. In the engine illustrated, it will be noted that the sleeve is driven at crankshaft speed for engine operation on a two stroke cycle.

Pistons 21 are operably associated with each of the engine cylinders and are arranged to be operatively connected with the eccentric 28 carried by the crankshaft by means of suitable connecting rods 29 and intermediate connections 30 which operatively connect the connecting rods with the crankshaft eccentric 28.

In the present embodiment of my invention I prefer to provide an eccentric 28 on the engine 10 crankshaft 12, this eccentric having suitably secured thereto, the inner bearing ring structure 31, this ring structure preferably comprising a pair of rings having outwardly extending annular flanges or ribs 32 which serve to locate the 15 needle bearings 33 or other suitable anti-friction devices, the eccentric having a diameter sufficiently large to accommodate all the connecting rod pads of one bank of cylinders without interference of one with the other.

20 A floating ring 34 is arranged to encircle the crankshaft eccentric 28 and have a bearing on the needle bearings or anti-friction devices 33. Thus rotation of the eccentric 28 will impart a rolling action to the needle bearings 33 and consequently the angular movement of the floating ring 34 is less than the angular movement of the eccentric 28.

This floating ring 34 is provided with a central outwardly extending annular rib or flange 35 which serves to position or otherwise locate the needle bearings or other suitable anti-friction devices 36 arranged in bearing relation with the outer cylindrical surface of the floating ring. The inner end of each of the connecting rods has 35 secured thereto a pad 37 having an inner arcuate surface which is arranged concentric with the cylindrical surface of the eccentric and is arranged to have a bearing on the anti-friction devices or needle bearings 36.

40 In addition to the locating means carried by the floating ring and inner bearing ring 31, it will be noted that these outer series of needle bearings or anti-friction devices are suitably held in position by the retaining members which 45 will prevent lateral displacement of same. The retaining members preferably comprise a ring 38 mounted around the annular rib 35 and extending beyond the sides of said annular rib to overlie the needle bearings 36 as clearly shown 50 in Fig. 2. Additional retaining rings 39 are secured to the side faces of said floating ring by means of bolts or screws 40 and these side retaining rings are arranged to engage the outer ends of the needle bearing 36, and are provided 55 further with a lip portion 41 partially overlying the outer ends of said needle bearings. It will be furthermore noted that these side retaining members or rings cooperate with the central retaining ring 38 to definitely retain the anti-friction devices or needle bearings in position, and also engage the side walls of the connecting rod pad 37 to prevent lateral displacement of 60 said connecting rod pad as well as the lateral displacement of the anti-friction devices 36.

65 It will be noted that the floating ring shown in the present assembly is provided with anti-friction devices engaging the inner and outer cylindrical surfaces thereof, and respectively positioned intermediate the floating ring and crankshaft eccentric, and the floating ring and

the inner arcuate surface of said pad carried by the engine connecting rod.

Rings 44 are employed to retain the connecting rods substantially in position, these being a pair of rings 44 for each set of connecting rods in each bank, which are secured together by bolts 45 preferably extending between each connecting rod. Each pad is grooved as at 46 to provide an arcuate seat portion for the associated ring (see Fig. 1). These rings 44 are particularly adapted 10 for retaining the rods in position while engine is inoperative and while engine is being started.

15 It will be noted that the present assembly provides for efficient motor operation in that there is a minimum of friction due to the fact that there is a minimum of sliding of the connecting rod pad with respect to the floating ring assembled between said pad and crankshaft eccentric 28. The addition of the needle bearings or other suitable anti-friction devices between 20 the pads and floating ring and the floating ring and eccentric 28 provide a construction in which friction is maintained at an absolute minimum, thereby minimizing engine power losses.

In addition to the rings 44 for holding down 25 the connecting rod or forcing the pad 37 against the anti-friction bearings between it and the floating ring 34, further means are made possible because of the fact that the engine herein illustrated is operated as a two stroke cycle engine, and all forces are exerted inwardly toward the engine crankshaft during engine operation. Due to the curvature of the inner arcuate surface of the connecting rod pad, it will be noted that tilting of the piston is prevented and the 30 connecting rod will tilt with respect to the cylinder axis as the eccentric crank moves around, the pad merely shifting or slightly sliding on the anti-friction devices carried around the outer cylindrical surface of the floating ring. It may 40 be further noted that the crankshaft bearings are sufficiently large to permit the longitudinal assembly of the crankshaft in the crankcase.

45 Although I have illustrated but one form of my invention and have described in detail but a single application thereof, it will be apparent to those skilled in the art to which my invention pertains that various modifications and changes may be made therein without departing from the spirit of my invention or from the scope of the 50 appended claim.

What I claim as my invention is:

A radial engine crank assembly including a crankshaft having a crank portion, a plurality of connecting rods one for each engine cylinder 55 and each provided with a slipper type pad at the inner end of the rod, means operatively connecting said connecting rods with said crankshaft crank portion including a floating ring encircling said crank portion and provided with an outer 60 annular rib, anti-friction devices intermediate said crank portion and said floating ring, anti-friction devices supported on the outer surface of said ring and positioned by said annular rib, said connecting rod pads bearing on said last 65 mentioned anti-friction devices, and retaining rings secured to said floating ring for restraining said last mentioned anti-friction devices and said connecting rod pads from lateral displacement.

70 EDWARD T. VINCENT.
